D5-16

EX

D5379

OR

D 15,240

DESIGN.

—
P. GROEBER.

WALL PAPER.

No. 15,240.

Patented Aug. 12, 1884.

UNITED STATES PATENT OFFICE.

PAUL GROEBER, OF NEW YORK, N. Y.

DESIGN FOR WALL-PAPER.

SPECIFICATION forming part of Design No. 15,240, dated August 12, 1884.

Application filed April 11, 1884. Term of patent 3½ years.

To all whom it may concern.

Be it known that I, PAUL GROEBER, a citizen of the United States, residing in the city of New York, county and State of New York, have invented and produced a new and original Design for Wall or Ceiling Covering, which is especially intended as a frieze.

The drawing represents a front plan view of the design.

10 This design is in the modern Renaissance style, consisting of floral and scroll work treated conventionally.

15 The center of the design shows an open flower, a, from the corolla of which spring scroll-leaflets b, which expand as they extend upward, forming a vase-like projection, in the mouth of which is placed a group of flower-buds, c. Springing also from the flower a, on the right and left of the last-mentioned figures, 20 are branches d d, having at their terminals leaves and cluster of flower-buds. On either side of the flower a is a branching scroll, e, one branch of which gracefully extends upward, clasping the branch d, forming a volute 25 in its termination. Other branches, f, incline downward, where a volute, g, having rosette and husk with fruit, forms its termination. Center branches, h h, of the same system of scrolls pass to the right and left to the extreme 30 lateral limits of the design, each terminating in an Ionic volute, i i. From these volutes gracefully hang a floral wreath of semicircular form composed of masses of leaves k k, all pointing in one direction, the surface of 35 which is decorated with rosettes l l, representing expanded flower-blooms of different sizes.

The design laterally and outside of the wreath is occupied with perpendicular sheaths m of foliation, with beads of seeds.

40 At the base of the design and overlapping the lower border is a rosette, n, which is the key to the whole design, as from its center springs the system of scroll-work before described, which, in combination with other 45 ornamentation, unites to form a symmetrical figure. Upper and lower borders, o o, are provided the former ornamented with a band of return-leaves, and the latter with line and pyramid work.

50 I claim—

The design herein described and shown, consisting of a central flower from which spring scroll-leaflets, forming the general outline of a vase, in the mouth of which rests a group of 55 flower-buds, a branch, one on each side, also springing from the central flower, having at their ends buds and leaves, sets of branches in the form of scrolls on either side of the central flower, one branch on each side extending upward, the upper end of which forms a volute which embraces the stem of a flower, another branch extending farther laterally, and also upwardly and terminating in a 60 volute, and another branch extending laterally and downwardly and terminating in a volute with husk and fruit, and a semicircular wreath ornamented with rosettes extending across the central flower, and a rosette placed centrally at the lower edge of the design, and 65 overlapping the lower border, and a border 70 above and below the design.

PAUL GROEBER.

Witnesses:

PHILLIPS ABBOTT,
JOHN MICHELS.